PRESTON, Jr. & BARRY.

Flat Iron Heater.

No. 39,171.

Patented July 7, 1863.

Fig. 1.

Fig. 2.

UNITED STATES PATENT OFFICE.

O. W. PRESTON, JR., AND CHARLES BARRY, OF CORNING, NEW YORK.

IMPROVEMENT IN SAD-IRONS.

Specification forming part of Letters Patent No. 39,171, dated July 7, 1863.

To all whom it may concern.

Be it known that we, O. W. PRESTON, Jr., and C. BARRY, of Corning, in the county of Steuben and State of New York, have invented a new and useful Improvement in Sad-Irons and Heaters; and we do hereby declare that the following is a full, clear, and exact description of the same, reference being had to the accompanying drawings, making a part of this specification, in which—

Figure 1 is a vertical central section of our invention, taken in the line *x x*, Fig. 2; Fig. 2, a horizontal section of the same, taken in the line *y y*, Fig. 1.

Similar letters of reference indicate corresponding parts in the two figures.

This invention relates to a new and useful improvement in sad-irons or "flat-irons," as they are frequently termed; and it consists in constructing the iron with a shell or case, in which a sliding or adjustable heater is placed and arranged in such a manner that the iron may be applied to a coal-oil lamp and made to serve as a draft chimney for the same, and be heated very expeditiously, a cold iron being applied to the lamp as a heated one is removed, in order that the lamp may always be provided with a chimney and a heated iron be always at command during the process of ironing.

To enable those skilled in the art to fully understand and construct our invention, we will proceed to describe it.

A represents a lamp provided with an ordinary coal-oil burner, B, and having a stand, C, attached to it which may be constructed of sheet-metal plate, bent in the form as shown in Fig. 1, and having its lower ends secured to the fountain or body of the lamp. The upper horizontal part, *a*, of the stand C has an aperture made in it directly over the apex of the cone or deflector *b*, to admit of the flame of the lamp passing through. (See Fig. 1.)

D represents the iron, which is composed of a shell, *c*, having a handle, *d*, attached to it at one side, and two parallel guide-rods, *e e*, within it. Within the shell a heater, *f*, is placed and fitted on two guide-rods, *e e*. This heater extends the whole length of the shell, and is equal to it in width, but it is not so deep or thick as the shell—not quite half as deep. (See Fig. 1.) By this means the heater is allowed a certain degree of play or movement within the shell, and a space allowed between the heater and the inner side of the shell to form a draft-chimney, as will be fully understood by referring to Fig. 1.

From the above description it will be seen that in order to heat the iron the latter is inserted or turned bottom upward, so as to cause the heater *f* to fall against the side of the shell which has the handle *d* attached. The iron is then placed endwise on the stand C, and the flames of the lamp will heat both the heater *f* and the bottom *a'* of the shell. When a heated iron is removed from the stand C, a cold one is placed upon it so as to keep the lamp supplied with a heated iron whenever one is required. It will be understood, of course, that when the iron is in use, the heater *f* rests upon the bottom *a'* of the shell.

Having thus described our invention, what we claim as new, and desire to secure by Letters Patent, is—

The iron D, composed of a shell, *c*, and a sliding or adjustable heater, *f*, fitted within it and arranged substantially as shown, so as to serve, while being heated, as a draft-chimney for the lamp, as set forth.

O. W. PRESTON, JR.
CHARLES BARRY.
